UNITED STATES PATENT OFFICE.

WILLIAM D. BROCK, OF MILWAUKEE, WISCONSIN.

FRICITION-CLUTCH.

SPECIFICATION forming part of Letters Patent No. 308,872, dated December 9, 1884.

Application filed April 18, 1884. (No model.)

To all whom it may concern:

Be it known that I, WILLIAM D. BROCK, a citizen of the United States, residing at Milwaukee, in the county of Milwaukee and State 5 of Wisconsin, have invented certain new and useful Improvements in Friction - Clutches; and I do hereby declare the following to be a full, clear, and exact description of the invention, such as will enable others skilled in the 10 art to which it appertains to make and use the same, reference being had to the accompanying drawings, and to letters or figures of reference marked thereon, which form a part of this specification.

15 My invention relates to improvements in that class of friction-clutches by which motion is communicated from a loose band-pulley to its supporting-shaft.

Figure 1 represents a vertical section of the 20 band-pulley upon its supporting-shaft provided with my clutch shown in its closed position. Fig. 2 is a vertical section of the clutch removed from the band-pulley.

Like parts are represented by the same reference-letters in both views.

25 A is a pulley-shaft. B is a loose band-pulley, which revolves freely upon the shaft A, except when it is engaged by the friction-clutch C. The friction-clutch C is rigidly affixed to the shaft A by set-screw D and revolves with it. Thus, when the clutch is caused to engage the pulley, motion is communicated from the pulley through the clutch to the shaft. The clutch consists of the laterally-moving collar E, provided with lever F, arm G, having sleeve H rigidly affixed to the shaft A, link I, lever J, and jaws K and L. The jaws K and L are held against the surfaces of the arm G by bolts M. The center of the bolts 30 M are rigidly secured in holes in the arm G, and their projecting ends pass through slots provided therefor in said jaws, which slots permit of the free movement of said jaws toward and from the shaft as the jaws are opened and closed. If desired, the jaws may be held in contact with said arm G by dovetailed tongue-and-groove ways and said bolts dispensed with. The arm J is provided with circular enlargements O and P, operating in 35 slots R R, provided therefor, in said jaws K and L.

To the outer end of the sleeve E is attached a shifting-lever, S, of the ordinary construction, operating in the groove T, whereby said collar may be readily moved toward the right 55 or left on its supporting-shaft both when revolving and at rest.

When desirous to communicate motion from the revolving pulley B to the shaft, the lever S is thrown toward the right, as 60 shown in Fig. 1, whereby motion is communicated from the sleeve E through the lever F and link I to the lever J, (said lever J being pivoted to arm G by bolt U,) whereby its long arm is thrown upward and its short arm 65 thrown downward, thereby moving the jaw K outward against the inner surface of the rim of the pulley, while the jaw L is drawn inward against the periphery of said pulley, and the rim thus firmly grasped between said jaws, as 70 shown in Fig. 1, and said jaws and shaft caused to rotate with the pulley. When desirous to stop the motion of the shaft, said lever S is moved toward the left, whereby all the connecting mechanism between said lever S and 75 said jaws is inversely moved and said jaws are opened, as shown in Fig. 2, thus relieving the pulley from the grasp of said jaws, when it is free to rotate independently of said shaft.

To prevent the band from coming in contact with the friction-clutches, a shoulder or elevation, α , is formed between the band-surface of the pulley and the friction-surface against which said clutch engages, whereby 85 said clutch is prevented from interfering with the action of the band. The space between the jaws K and L is varied to correspond to the various thicknesses of the pulley-flanges or to conform to the thickness of the flange 90 when worn away by changing the adjustment of the lever F, which lever is rigidly held and adjusted at any desired angle to the sleeve E by the screw b and nuts d d.

For a flange of greater thickness the nuts 95 d are screwed up on the screw b, whereby said jaws are separated, and for a thinner flange said nuts d are screwed downward, whereby said jaws are brought nearer to each other. The jaws being once adjusted to conform to 100 the flange, they are opened and closed by simply shifting said lever S, as mentioned.

The bearing-surfaces O and P are made in the circular form shown to permit of the change of inclination of the lever J within the slots of the jaws, while said bearings act uniformly against the upper and lower bearing-surfaces of said slots at any and all points of inclination of said lever.

Having thus described my invention, what I claim as new, and desire to secure by Letters 10 Patent, is—

1. The combination, with a shaft and loose pulley adapted to run freely on said shaft, of a clutch rigidly secured to said shaft, having two inversely-moving radial jaws adapted to 15 engage one upon the periphery and one against the interior of the pulley-flange, said jaws being connected by lever J, link I, and lever F, with a laterally-moving sleeve and shifting-lever, whereby they may be simultaneously 20 opened and closed as said lever is moved toward the right and left, substantially as set forth.

2. The combination of shaft A, loosely-revolving pulley B, clutch C, consisting of arm G, rigidly attached to said shaft, jaws K and 25 L, secured to said arm G, bolts M M, lever J, having circular enlargements O and P, secured to said arm by pivotal bolt U, link I, lever F, sleeve E, and shifting-lever S, all substantially as and for the purpose specified.

3. In a friction-clutch, the combination of pulley B, arm G, jaws K and L, lever J, link I, adjustable lever F, sleeve E, screw b, and adjusting-nuts d d, said jaws K and L being adapted to be adjusted to grasp pulley-rims 30 of different thicknesses by the adjustment of said lever F, as set forth.

In testimony whereof I affix my signature in presence of two witnesses.

WILLIAM D. BROCK.
